(57) **CLAIM**

The ornamental design for a LED utility light, as shown and described.

DESCRIPTION

FIG. 1 is a top perspective view of the LED utility light.

FIG. 2 is a top view of the LED utility light.

FIG. 3 is a bottom view of the LED utility light.

FIG. 4 is a side view of the LED utility light, opposite side identical thereto; and,

FIG. 5 is an end view of the LED utility light, opposite end identical thereto.

The broken lines shown in the drawings are for the purpose of illustrating portions of the LED utility light and form no part of the claimed design.
